CONTACT MECHANISM

Andrew J. McCannell, Albany, N. Y., and William C. Morris, Darby, Pa., assignors to General Electric Company, a corporation of New York

Application September 23, 1942, Serial No. 459,354

9 Claims. (Cl. 200—168)

Our invention relates to improvements in contact mechanisms for electroresponsive devices and more particularly highly sensitive quickly acting relays, and especially relays which operate in response to predetermined abnormal conditions of an electric circuit.

In order to obtain fast contact controlling action from relays which respond to faults on electric circuits, it is desirable to use small contact gaps. Also, regardless of the magnitude of the energy ordinarily available to effect a circuit closing operation of the contacts, it is often desirable to use a relatively weak return spring in order to obtain maximum sensitivity of response. However, these two desirable features, that is, small gap and weak return spring, result in a hazard if the relay is subjected to shock since the movable contact may readily be shock-actuated to cause a circuit closing operation of the relay contacts. This may be serious, particularly if, as in the case of a differential relay, there is only one relay controlling the trip circuit of a circuit breaker because the result would be an unnecessary interruption in the much desired continuity of service. Furthermore, in certain relays, such as those which respond to the direction of flow of power, there can occur in some cases, such as clearing a fault behind a relay, a sudden change in the direction of the force or torque acting on the movable contact with such magnitude in the circuit opening direction as to cause a quick rebound through the small contact gap to the circuit closing position since the restraint against movement in this direction is small. As before, this might result in an unnecessary and undesirable circuit breaker tripping operation even though the relay may be cooperating with some other fault responsive relay, such as an instantaneous overcurrent relay whose contacts are in series with the contacts of a power directional relay.

An object of our invention is to provide an improved contact mechanism for electroresponsive devices, relays and the like, such that the advantages accruing from small contact gaps and weak return springs may be retained without danger of false operation because of shock and rebound. Another object of our invention is, in effect, momentarily so to increase the contact gap when the relay operating force or torque is strong in the circuit opening direction as to require a closing time greater than the normal closing time. These and other objects of our invention will hereinafter appear in greater detail.

In accordance with our invention, we provide

5 a shock resistant backstop comprising a cushioning member carried by the movable contact of the relay and engageable with a movable member of sufficient inertia to absorb shock. Also 10 in accordance with our invention, the movable member is arranged directly to partake of the movement of the movable contact to an amount dependent on the circuit opening effect of the contact actuating means of the relay whereby proportionately to increase the contact gap and thus minimize the danger of rebound reclosing as well as requiring a greater circuit closing time under certain desired conditions.

15 Our invention will be better understood from the following description when considered in connection with the accompanying sheet of drawings, and its scope will be pointed out in the appended claims.

20 In the accompanying sheet of drawings, Fig. 1 is a front elevation of a relay having a contact mechanism embodying my invention; Fig. 2 is a top plan view of the relay and contact mechanism shown in Fig. 1; Fig. 3 is a vertical sectional view on the line 3—3 of Fig. 2; and Fig. 4 is a vertical sectional view, similar to Fig. 3, illustrating a modification of our invention.

25 For the purpose of illustrating our invention, we have shown an embodiment thereof as applied to a relay 5 of the induction cylinder type such as disclosed, for example, in United States Letters Patent Reissue 21,813, issued May 27, 1941. While our invention is particularly well adapted to a quickly acting high torque relay device, such as disclosed in said Letters Patent, it is to be distinctly understood that its application is general and not limited to the specific structure herein shown.

30 The illustrated relay structure comprises a magnetic stator 6 which is hollow and has a plurality of inwardly projecting poles, provided with suitable energizing windings. Within the hollow of the stator 6 is another suitably mounted stator and mounted on a shaft 7 for rotation in the air gaps between the stators is a hollow cylindrical electric current conducting member, all as set forth in said Letters Patent. This actuating means or motor structure is mounted between suitable nonmagnetic end frames 8 and 9 preferably having high heat dissipating properties. Above the upper end frame 8 is a supporting structure or contact head 10 which is of suitable insulating material and which carries a suitably adjustable bearing 11 for the upper end of the shaft 7. Mounted on this shaft so as to turn 35 therewith is a movable contact carrying member

12 to which is secured a suitable electric current conducting strip 13 provided with a contact 14. The member 12, referring to Fig. 2, is biased for counterclockwise movement by a relatively weak spiral spring 15, the inner end 16 of which is in conductive relation with the strip 13 and the outer end 17 of which is conductively secured to a ring 18 of suitable conducting material.

In order to vary the counterclockwise torque of the spring 15 and thereby change the sensitivity of the relay, the ring 18 is rotatably positioned in an insulating support 19 mounted on the contact head 10. To hold the ring in any desired position, it may be clamped against its support 19, as shown in Fig. 2, by suitable means such as a threaded member 20 which passes through terminal 21 of a lead 22, the support 19, the ring 18 and a clamping plate 23 set in a notch on the lower side of the support 19. With this arrangement, it will be observed that the spring 15 also acts as a lead-in conductor between the ring 18 and the contact strip 13. Cooperating with the movable contact 14 is a relatively stationary contact 24 which is illustrated as of the anti-rebound type disclosed in United States Letters Patent 2,098,032, issued November 2, 1937. This anti-rebound structure comprises a split nut or support 25 provided with a threaded bushing 26 and a clamping screw 27, all mounted on the contact head 10 with the threaded opening in the bushing suitably inclined to the base of the contact head 10. Screwed into the bushing 26 is a threaded barrel or cylinder 28 within which there is a rollable member or ball which normally rests against a diaphragm at the lower end of the housing. Between the diaphragm and a resilient contact support which carries the contact 14 is a spacing ring. The contact support, ring and diaphragm are held in place with the ball in the housing 28 by a collar 29, all as disclosed in said Letters Patent 2,098,032.

Since for fast circuit controlling action, a small gap, preferably not exceeding three sixty-fourths of an inch, between the contacts 14 and 24 is essential and for maximum sensitivity of response the counterclockwise torque of the spring 15 must be small; it is apparent that any shock transmitted to the relay could readily effect an undesirable circuit closing operation of the contacts. This would, if these were the only contacts in the circuit of the trip coil of a circuit breaker as in the case of a differential relay, cause a false circuit opening operation with a possible interruption in the much desired continuity of service. In order to avoid this undesirable shock closing contact operation, we provide a shock absorbing means which, as shown more clearly in Fig. 3, comprises suitable cushioning means such as a felt pad 30 mounted on the contact carrying member 12. As shown, this pad is set in a cup 31 which is secured to a metallic strip 32 similar to the contact strip 13 and similarly mounted on the member 12. In the path of movement of the pad 30 so as to partake of movement of the member 12 is a movable member such as a ball 33 which is reliable in a suitably mounted guideway such as a cylindrical housing 28'. This housing is screwed into a split and threaded bushing 26' which is so mounted in a split nut or support 25' as to cause the ball 33 to tend to roll down hill toward the pad 30. The bushing 26' and the housing 28' are held in position by a clamping screw 27'. The ball 33 is maintained in the housing 28' by a collar 29' having a suitable opening to allow the desired

movement of the pad 30. With this arrangement, it will be noted that any shock to the relay tending to cause a circuit closing movement of the contact carrying member 12 is ineffective since the ball 33 and the member 12 apparently remain stationary in space although both are free to move together in the circuit opening direction.

In addition to the antishock feature, relays 10 embodying our invention are particularly effective under other conditions tending to cause false operation. Thus, for example, if the relay in case of a fault is subjected to a torque in the contact opening direction, the ball 33 will be 15 moved upwardly in the housing 28' an amount dependent upon the magnitude of the torque within the limit of counterclockwise motion of the contact carrying member 12. During this movement the ball exerts a substantially constant 20 countereffect which is independent of the amount of the contact separation. This movement of the ball permits a relatively large increase in the gap between the contacts 14 and 24 with a 25 steady follow-up by the ball 33 when the torque is removed by the clearing of a fault through the opening of a circuit breaker near the fault. Thus, for example, in the case of a ground directional relay, when a ground fault in the non-tripping direction is cleared, tendency for rebounding action or shock to cause a closing of 30 the contacts 14 and 24 is substantially eliminated.

Also if, in the process of clearing a fault, the 35 opening of the first circuit breaker results in a reversal of flow of ground fault power, this sudden reversal will not quickly effect the closing of the directional relay contacts because of the contact gap increase during the non-tripping direction of ground fault power flow. This is particularly advantageous when a ground fault power 40 directional relay is arranged with its contacts in series with the contacts of an instantaneous overcurrent relay in the circuit of the trip coil of a circuit breaker, as is the usual practice in the art of circuit protection. With such an arrangement, there is the possibility that with the reversal of ground fault power flow the contacts of the power directional relay may close before the contacts of the overcurrent relay can open. 45 This would, of course, cause a false tripping of the circuit breaker which is highly undesirable. However, if the power directional relay embodies our invention, then a fault power flow in the nontripping direction will produce a relatively high counterclockwise torque to push the ball 50 33 up in the housing 28' and thereby increase the gap between the contacts 14 and 24 and hence the time to close these contacts. This gap can readily be made sufficient to insure the opening of the instantaneous overcurrent relay contacts 55 before the directional relay can close its contacts when the ground power flow reverses.

Likewise, in a differential relay of a type well known to the art wherein there is a large restraint torque on heavy through faults to keep 60 the contacts open, the contact gap between the contacts 14 and 24 is again materially increased. Then when the fault is cleared by the opening of a circuit breaker, the loss of the high restraint torque is not effective through rebound, shock or otherwise to cause a false closing of the contacts 14 and 24.

From the foregoing, it will be observed that the combination of the ball 33 and the cushioning member 30 eliminates the possibility of contact closure with any shock ordinarily to be ex-

pected. Also, with a contact opening torque or force exerted by the electromagnetic actuating means in a direction to increase the contact gap, the rebound is eliminated without any special features such as slip clutches and the adjustment thereof. Moreover, the possibility of the increased gap, when a relay embodying our invention is used with another relay, such as the instantaneous overcurrent relay mentioned above, eliminates the necessity for special features to insure the dropout of the instantaneous relay before the closing action of the directional relay or to prevent operation of the instantaneous relay when the fault is initially in the direction to retain the contacts in the open position.

While the cushioning means, such as the felt 38, is of particular value in absorbing the upward component or lift on the ball 33 due to shock, our invention may be used without this cushioning means, particularly when the contact gap increase effect is the principal feature desired. Thus, the embodiment of our invention shown in Fig. 4 may be employed. In this embodiment, the movable contact carrying member 12 is in direct engagement with the ball 33 without any intervening cushioning means 38. It will be noted that in either of the modifications shown in Figs. 3 or 4 the actuation of the ball 33 upwardly in its housing is not accomplished by increasing the bias of or storing energy in a spring, which would tend to cause rebound. In other words, after the movable contact carrying member 12 engages the movable member 33, the countereffect of the backstop means opposed to the circuit opening effect of the actuating means is substantially constant regardless of the extent of the contact separation.

While we have shown and described our invention in considerable detail, we do not desire to be limited to the exact arrangements shown, but seek to cover in the appended claims all those modifications that fall within the true spirit and scope of our invention.

What we claim as new and desire to secure by Letters Patent of the United States is:

1. In a highly sensitive quickly acting electro-responsive device wherein actuating means are arranged to effect the circuit closing operation of relatively fixed and movable cooperating contacts and means is provided for effecting a circuit opening of the contacts when the device is substantially deenergized; shock-resistant backstop means for maintaining a relatively small gap between said contacts when the device is substantially deenergized comprising a guideway having one end adjacent the movable contact, a member movable in said guideway and biased toward said one end thereof, and a cushioning member mounted on the movable contact and engageable with said movable member when the contacts are separated more than a predetermined amount.

2. In a highly sensitive quickly acting electro-responsive device wherein actuating means are arranged to effect the circuit closing operation of relatively fixed and movable cooperating contacts and a relatively weak means is provided for effecting a circuit opening operation of the contacts when the device is substantially deenergized; shock-resistant backstop means for maintaining a relatively small gap between said contacts when the device is substantially deenergized comprising a cylindrical housing having an open end adjacent the movable contact and

inclined downwardly toward said contact, a relatively heavy ball in said housing, and a cushioning member mounted on the movable contact and engageable with said ball when the contacts are separated more than a predetermined amount.

3. In a highly sensitive quickly acting electro-responsive device wherein actuating means are arranged to effect circuit controlling operations of relatively fixed and movable cooperating contacts and a relatively weak resilient means is provided for effecting a circuit opening operation of the contacts when the device is substantially deenergized; shock-resistant backstop means for maintaining a contact gap less than three sixty-fourths of an inch when the device is substantially deenergized comprising a cylindrical housing having an open end adjacent the movable contact and inclined downwardly toward said contact, a relatively heavy ball in said cylindrical housing arranged directly to partake of the movement of the movable contact and movable thereby uphill in the housing an amount dependent upon the circuit opening effect of the actuating means proportionally to increase the contact gap, and a cushioning member mounted on the movable contact and engageable with said ball when the contacts are separated more than a predetermined amount.
4. In an electroresponsive device wherein actuating means are arranged to effect the circuit closing operation of relatively fixed and movable cooperating contacts and a relatively weak means is provided for effecting a circuit opening operation of the contacts when the device is substantially deenergized; shock-resistant backstop means for limiting the gap between said contacts to a value less than three sixty-fourths of an inch when the device is substantially deenergized comprising a cylindrical housing inclined downwardly toward the movable contact with one end adjacent thereto, a ball in said housing, and a felt pad mounted on the movable contact and engageable with said ball when the contacts are separated more than a predetermined amount.

5. In an electroresponsive device wherein actuating means are arranged to effect the circuit closing and circuit opening operations of a relatively fixed contact and a movably supported cooperating contact and a relatively weak means is provided for effecting a circuit opening operation of the contacts; means for limiting the contact separation under the effect of only said relatively weak means to a value less than three sixty-fourths of an inch arranged to permit an effective increase in the separation of the contacts when the actuating means tends to cause a circuit opening operation of the contacts comprising a cylindrical housing inclined downwardly toward the movable contact and a relatively heavy ball in said housing for exerting on the support of said movable contact a substantially constant counter effect to balance the circuit opening effect of said relatively weak means, said ball being directly engageable by the support of the movable contact when the contacts are separated by said amount and movable uphill in the housing an amount dependent on the circuit opening effect of the actuating means proportionally to increase the separation of the contacts.
6. In a highly sensitive quickly acting electro-responsive device wherein actuating means are arranged to effect the circuit controlling op-

erations of a relatively fixed contact and a movably supported cooperating contact and separate means is provided for effecting a circuit opening operation of the contacts when the device is substantially deenergized; shock-resistant backstop means for limiting the contact separation to a relatively small amount when the device is substantially deenergized comprising a movable member for exerting on the support of said movable contact a substantially constant counter effect to balance the circuit opening effect of said separate means, said movable member being directly engageable by the support of said movable contact when the contacts are separated more than a predetermined amount.

7. In a highly sensitive quickly acting electro-responsive device wherein actuating means are arranged to effect circuit controlling operations of a relatively fixed contact and a movably supported cooperating contact and a relatively weak resilient means is provided for effecting a circuit opening operation of the contacts; backstop means for limiting the contact gap to a value less than three sixty-fourths of an inch when the device is substantially deenergized comprising a cylindrical housing having an open end adjacent the movable contact and inclined downwardly toward said contact, a relatively heavy ball in said cylindrical housing for exerting on the support of said movable contact a substantially constant counter effect to balance the circuit opening effect of said resilient means, said ball being directly engageable by the support of the movable contact for movement uphill in the housing an amount dependent upon the circuit opening effect of the actuating means proportionally to increase the contact gap.

8. In an electroresponsive device wherein actuating means are arranged to effect circuit controlling operations of a relatively fixed contact and a movably supported cooperating contact

- and a relatively weak means is provided tending to effect a circuit opening operation of the contacts; means for limiting the contact separation under the effect of only said relatively weak means to a value less than three sixty-fourths of an inch arranged to permit an effective increase in the contact gap when the actuating means tends to cause an increase in the separation of the contacts comprising a cylindrical housing inclined downwardly toward the movable contact with one end adjacent thereto and a ball in said housing for balancing the effect of said weak means when the contact separation is substantially equal to said value, said ball being directly engageable by the support of said movable contact and movable uphill in the housing an amount dependent upon the magnitude of the circuit opening action of said actuating means.
- 10 9. In a highly sensitive quickly acting electro-responsive device wherein actuating means are arranged to effect the circuit controlling operations of a relatively fixed contact and a movably supported cooperating contact and separate means is provided for effecting a circuit opening of the contacts when the device is substantially deenergized; backstop means for limiting the separation of the contacts to a relatively small value in response to the effect of only said separate means comprising a guideway having one end adjacent the movable contact, and means for exerting on the support of said movable contact a substantially constant counter effect to balance the circuit opening effect of said separate means comprising a member movable in said guideway biased toward said one end thereof said member being directly engageable by the support of said movable contact for movement in said guideway against said bias when the contacts are separated more than said value
